UNITED STATES PATENT OFFICE.

ROYAL N. DAVIDSON, OF WEAVERVILLE, CALIFORNIA.

WATER-WHEEL.

SPECIFICATION forming part of Letters Patent No. 253,267, dated February 7, 1882.

Application filed September 2, 1881. (No model.)

To all whom it may concern:

Be it known that I, ROYAL N. DAVIDSON, of Weaverville, county of Trinity, State of California, have invented an Improved Water-
5 Wheel; and I hereby declare the following to be a full, clear, and exact description thereof.

My invention relates to that class of water-wheels which is operated by the forcible discharge of a stream of water upon the buckets
10 or flanges in the rim of the wheel, and are commonly known as "turbine water-wheels."

It consists in certain details of construction, as hereinafter described and specifically claimed.

Referring to the accompanying drawings,
15 Figures 1 and 2 are perspective views of my wheel. Fig. 3 is a vertical section.

Let A represent one side of a wheel having a central axis, B, about which it revolves. The side A is convexed to its center in conical
20 form. On the front side of A are the flanges or buckets C: These are hollowed or dished out at the periphery of the wheel, and are curved inward toward the center, gradually tapering, as shown. Their inner ends are
25 therefore much narrower than their outer ends, the buckets being made to conform on one side to the convexity of the side A, and on the other side being made straight. Upon their outer or straight sides is secured a rim, D,
30 forming the other side of the wheel. This rim has an opening in the center, so that it really amounts to a ring or band inclosing the outer or dish-shaped ends of the buckets, while leaving the inner ends exposed for the discharge
35 of the water. The apex of the side A is about in the same plane with the rim D, so that the water-spaces formed by the buckets are contracted toward the center both in width and depth.

40 The wheel is intended to be properly mounted, either vertically or horizontally, and the stream of water directed upon each successive flange or bucket at a point in said bucket near its outer end. The force of the stream revolves

the wheel. When the stream first strikes the 45 bucket its velocity is much greater than that of the wheel, but it soon loses a great portion of its force, and were it allowed to remain in the buckets at the point where it first strikes, it would act as a drag upon the wheel and retard its revolution, because of having lost its velocity to such an extent as to be less than that of the circumference of the wheel. But by my construction of the flanges or buckets the water is conducted away from the circumference toward the center, at which point the velocity of the wheel is less than at the circumference, and the diminished velocity of the stream will not therefore act as a drag upon the revolution. Because of the curvature of 60 the buckets a further force is generated by conducting the water to the center.

It will be seen that this is a central-discharge wheel. The force of the stream is directed against the buckets and against the conical 65 side of the wheel. After expending its force it is conducted toward the center, and because of the conical side A is discharged out of line with the power stream, and thus does not interfere with it, nor does the contents of one 70 bucket interfere with another.

Having thus described my invention, what I claim as new, and desire to secure by Letters Patent, is—

A water-wheel consisting of the convex or 75 conical side A, having a central axis, B, the tapering buckets or flanges C, secured upon the convex side and curved and tapering toward the center of the side A, and the rim or side D, with its open center, substantially as and for 80 the purpose herein described.

In witness whereof I have hereunto set my hand.

R. N. DAVIDSON.
